United States Patent Office

Des. 181,230
Patented Oct. 15, 1957

181,230

BAR OF SOAP

John Oster, Jr., Milwaukee, Wis., assignor to The John Oster Manufacturing Co., Milwaukee, Wis., a corporation of Wisconsin

Application April 10, 1957, Serial No. 45,665

Term of patent 14 years

(Cl. D73—1)

I claim:

The ornamental design for a bar of soap, as shown.
